ABSTRACT

The specification discloses a pivoted extension ladder comprising two pairs of legs having two ends pivotally coupled together such that the legs may be pivoted between first and second positions to form a self-supporting ladder and an extended ladder respectively. Means is provided for releasably holding the two pairs of legs together in the first position when the ladder is being used as a self-supporting ladder. In addition, stop means is formed on the two pair of legs at their ends which are pivotally coupled together for engagement with each other when the two pair of legs are moved to their second position to prevent the two pair of legs from pivoting beyond the second position.

3 Claims, 3 Drawing Figures

PIVOTED EXTENSION LADDER**SUMMARY OF THE INVENTION**

The object of this invention is to provide an economical, reliable, and easy-to-use extension ladder and which comprises two pairs of legs having two ends pivotally connected together such that the legs may be pivoted between first and second positions to form a self-supporting ladder and an extended ladder respectively. Means is provided for releasably holding the two pairs of legs together in their first position and in addition, stop means is formed on said two ends of said two pairs of legs respectively and which are adapted to engage each other when said two pairs of legs are moved to their second position to prevent the two pairs of legs from pivoting beyond said second position.

In a further aspect, the extension ladder comprises a first pair of legs joined by an upper cross piece at their top ends and by at least one cross piece at a position spaced from their top ends. In addition, there is provided a second pair of legs having first and second opposite ends. The second pair of legs are joined by at least one cross piece at positions spaced from their first ends. Means is provided for pivotally coupling said top ends of said first pair of legs and said first ends of said second pair of legs together to allow said first and second pair of legs to be pivoted, between first and second positions. Said first and second pair of legs at said first position form an acute angle relative to each other for forming a self-supporting ladder. Said first and second pair of legs at said second position form an angle of about 180° relative to each other for forming an extended ladder having an increased length for use for reaching greater heights. Means is provided for releasably holding said first and second pair of legs in said first position. In addition, stop means is provided on said first and second pairs of legs at their top and first ends respectively adapted to engage each other when said first and second pairs of legs are in their second position to prevent said first and second pairs of legs from pivoting beyond said second position.

BRIEF DESCRIPTION OF THE DRAWINGS

FIG. 1 illustrates the extension ladder of the present invention when moved to its extended position;

FIG. 2 illustrates the extension ladder when located in its retracted position for forming a self-supporting ladder; and

FIG. 3 illustrates a modified arrangement for pivotally coupling together two ends of the two pairs of legs forming the extension ladder.

DETAILED DESCRIPTION OF THE INVENTION

Referring now to FIGS. 1 and 2, the extension ladder is identified by reference numeral 21 and comprises a first pair of legs 23 and 25 and a second pair of legs 27 and 29. Legs 23 and 25 are joined together at their top ends 23A and 25A by an upper cross piece 31 and at positions spaced from the upper cross piece by cross pieces 33 and 35. Legs 27 and 29 have ends 27A and 29A hinged or pivotally connected to the ends 23A and 25A of legs 23 and 25 by bolts 37 and 39. Spaced cross pieces 41 and 43 are connected to the legs 27 and 29 at positions spaced from their ends 27A and 29A.

The two pairs of legs may be pivoted between a partially folded or retracted position, as illustrated in FIG. 2 to an extended position, as illustrated in FIG. 1. In the

partially folded or retracted position, the two pair of legs form an acute angle relative to each other and the ladder becomes a self-supporting ladder. In this position, the legs are held together by hooks 45 and 47 and eyes 49 and 51. Hooks 45 and 47 are pivotally connected to legs 23 and 25 respectively, by members 53 and 55 (not shown). It is noted that the cross pieces 31, 33 and 35 are flat members which are connected between the legs 23 and 25 at angles such that they in effect form level surfaces to allow one to step upward and to provide a better support when the ladder is being used as a self-supporting ladder.

The pair of legs 27 and 29 may be pivoted to an extended position, as illustrated at FIG. 1 by removing the hooks 45 and 47 from the eyes 49 and 51 and swinging the legs 27 and 29 upward in the direction of the arrow 56. In the extended position, the two pairs of legs 23, 25 and 27, 29 are at an angle of about 180° relative to each other. Connected to the top ends of legs 23 and 25 are stops 57 and 59 which are adapted to engage stops 61 and 63 formed at the ends 27A and 29A of legs 27 and 29 whereby when in the extended position, the two pairs of legs are prevented from pivoting beyond their 180° position. Thus, in the extended position, the pair of legs 23 and 25 form the bottom portion of the ladder and the pair of legs 27 and 29 form the top portion of the ladder and their ends 27B and 29B may be positioned against a wall or other object desired to be reached. The cross pieces 41 and 43 preferably are round and they have no preferred angular position relative to the legs 27 and 29 whereby when the legs 27 and 29 are pivoted to the extended position, and the ladder is being used as an extended ladder, the user may easily step on the cross pieces 41 and 43 at the proper angle. Thus, by making the cross pieces 41 and 43 round, either pair of legs of the ladder in its self-supporting position, may be used for stepping purposes, and the cross pieces 41 and 43, when the legs 27 and 29 are moved to the extended position, may be used also as stepping cross pieces.

In the preferred embodiment, the ladder is formed of aluminum. The cross pieces 31, 33, and 35 are welded to the legs 23 and 25 and cross pieces 41 and 43 are swaged to the legs 27 and 29, although they also could be welded. Cross pieces 31, 33, and 35 are welded to legs 23 and 25 at an angle such that they are level or nearly level when the ladder is being used as a self-supporting ladder or an extended ladder. Both pairs of legs 23, 25 and 27, 29 have right angled flanges to provide structural support. For storage purposes, when the ladder is not being used, the hooks 45 and 47 may be unhooked from their eyes 49 and 51 and the legs 27 and 29 folded inward toward legs 23 and 25 until the legs 27 and 29 engage stops 57 and 59 and hooks 45 and 47. In this position, the legs are folded together as far as possible forming a nearly flat folded ladder.

Referring to the embodiment of FIG. 3, there is illustrated a portion of one-half of the extension ladder showing two legs of each pair of legs. In this embodiment, the legs and stops, at their ends, are modified from that of the embodiment of FIGS. 1 and 2. Leg members 63, 65, and 67 are bolted together by bolts and nuts 69 and 71 to form a leg 68 corresponding with leg 23 of the embodiment of FIG. 1. Members 63 and 67 have enlarged, rounded heads 63A and 67A formed at their top ends respectively. Member 65 has a stop or shoulder 65A formed at its top end and a concave sur-

face 65B extending downward from the stop 65A. Thus, when the two members 63 and 67 are bolted together with the inner member 65 sandwiched in between, an open space is formed between the two heads 63A and 67A. The leg 73 corresponds with the leg 27 and has formed at its top end, an enlarged rounded head 73A which fits within the space formed between heads 63A and 67A of members 63, 65, and 67. A bolt 74 extends through apertures formed through heads 63A, 73A, and 67A to pivotally couple leg 73 to the leg formed by member 63, 65, and 67. The leg 73 has a stop 73B formed at its upper end, as illustrated in FIG. 3. The legs of the other half of the ladder are formed in a manner similar to legs 68 and 73 and also are pivotally coupled together in a similar manner. Leg 73 and its mate (not shown) are fixedly connected together at positions spaced from their pivot ends by cross pieces, one of which is illustrated at 41. Leg 68 and its mate (not shown) are fixedly coupled together by cross pieces, two of which are illustrated at 31 and 33. The cross pieces 31 and 33 are connected to the inner member 67 of leg 68 and to the corresponding inner member forming the mating leg of leg 68.

The legs 68 and its mate and 73 and its mate are adapted to be pivoted to a partially folded or retracted position and to an extended position similar to that shown in FIGS. 1 and 2. In the partially retracted position, hooks and eyes (not shown) are provided for holding the legs in their partially retracted position to allow the ladder to be self-supporting to be used for climbing purposes. When the ladder of the embodiment of FIG. 3 is to be extended, leg 73 and its mate are pivoted upward in the direction of the arrow 81 until stops 65A of leg 68 and its mate abut and engage stops 73B of leg 73 and its mate.

The ladder of the embodiment of FIG. 3 also may be formed of aluminum. Leg members 65 of leg 68 and its mate have a width less than the widths of members 63 and 67 to allow leg 73 and its mate to be pivoted inward toward leg 68 and its mate to form a nearly flat and folded ladder for storage purposes when the ladder is not being used.

As one example of the ladder of the embodiments of FIGS. 1-3, the ladder, in its folded or retracted position, may have a length of about two feet to form a short ladder and when extended forms a ladder of about four feet.

I claim:

1. A pivotal extension ladder comprising:
a first pair of leg means joined by an upper cross piece at their top ends and by at least one cross piece at a position spaced from their top ends,
a second pair of leg means having first and second opposite ends,
said second pair of leg means being joined by at least one cross piece at positions spaced from their first ends,
means for pivotally coupling said top ends of said first pair of leg means and said first ends of said second pair of leg means together to allow said first and second pair of leg means to be pivoted, between first and second positions,
said first and second pair of leg means at said first position forming an acute angle relative to each other for forming a self-supporting ladder,
said first and second pair of leg means at said second position forming an angle of about 180° relative to

each other for forming an extended ladder having an increased length for use for reaching greater heights,
means for releasably holding said first and second pair of leg means together in said first position, stop means on said first and second pair of leg means at their top and first ends respectively adapted to engage each other when said first and second pair of leg means are in their second position to prevent said first and second pair of leg means from pivoting beyond said second position,
said first and second pair of leg means having outward facing sides facing in opposite directions when said first and second pair of leg means are in their first position,
said outward facing sides of said first and second pair of leg means facing in the same direction when said first and second pair of leg means are in their second position,
said first pair of leg means defining the bottom portion of said ladder when extended,
said upper cross piece having a generally flat upper surface located at an angle relative to said first pair of leg means such that said upper surface is generally level when said first and second pair of leg means are located in their first position and supported on a level base,
said stop means comprising:
a first pair of stops located on opposite facing sides of said first pair of leg means, and
a second pair of stops formed on said second pair of leg means for engagement with said first pair of stops when said first and second pair of leg means are in their second position.
2. The ladder of claim 1 wherein:
said first ends of said second pair of leg means straddle the top ends of said first pair of leg means.
3. A pivotal extension ladder comprising:
a first pair of legs joined by an upper cross piece at their top ends and by at least one cross piece at a position spaced from their top ends,
a second pair of legs having first and second opposite ends,
said second pair of legs being joined by at least one cross piece at positions spaced from their first ends, means for pivotally coupling said top ends of said first pair of legs and said first ends of said second pair of legs together to allow said first and second pair of legs to be pivoted, between first and second positions,
said first and second pair of legs at said first position forming an acute angle relative to each other for forming a self-supporting ladder,
said first and second pair of legs at said second position forming an angle of about 180° relative to each other for forming an extended ladder having an increased length for use for reaching greater heights, means for releasably holding said first and second pair of legs together in said first position, each leg of said first pair of legs comprises an inner member and two outer members fixedly connected together such that said inner member is sandwiched between said two outer members, the top ends of said outer members extend beyond the top end of said inner members such that a slot is formed between said two outer members at their top ends,

each leg of said second pair of legs has its first end located in one of the slots of an associated leg of said first pair of legs for pivotal movement therein,
 each leg of said second pair of legs has a stop means formed on its first end for engagement with the inner member of its associated leg of said first pair of legs when said first and second pairs of legs are located in their second position to prevent said first and second pairs of legs from pivoting beyond said second position,
 10 said first and second pair of legs have outward facing sides facing in opposite directions when said first and second pair of legs are in their first position,

5

10

15

said outward facing sides of said first and second pair of legs facing in the same direction when said first and second pair of legs are in their second position, said first pair of legs forming the bottom portion of said ladder when extended,
 said upper cross piece having a generally flat upper surface located at an angle relative to said first pair of legs such that said upper surface is generally level when said first and second pair of legs are located in their first position and supported on a level base.
